United States Patent Office.

JAMES SWAN, OF SEYMOUR, CONNECTICUT.

Letters Patent No. 76,956, dated April 21, 1868.

IMPROVEMENT IN AUGER-HANDLES.

The Schedule referred to in these Letters Patent and making part of the same,

TO ALL WHOM IT MAY CONCERN:

Be it known that I, JAMES SWAN, of Seymour, in the county of New Haven, and State of Connecticut, have invented a new and improved Auger-Handle; and I do hereby declare that the following is a full and exact description thereof, which will enable others skilled in the art to make and use the same, reference being had to the accompanying drawings and to the letters of reference marked thereon.

This invention relates to a new and improved auger-handle of that class which are constructed with a view of a ready attachment of the handle to the auger-shank, and also a ready detachment therefrom, so as to admit of one handle being used for different augers.

The object of the invention is to obtain an auger-handle of the class specified, which will be simple in construction, strong, and durable, be capable of being applied to the auger-shank in a proper relative position therewith, without any difficulty whatever, and manufactured at a reasonable cost.

In the accompanying sheet of drawings—

Figure 1 is a plan sectional view of my invention.

Figure 2, a side sectional view of the same.

Similar letters of reference indicate like parts.

The auger-handle is composed of two parts, A B, of cast iron, tubular or hollow, and externally of the usual auger-handle form.

The inner end of the part A terminates in what may be termed a socket, *a*, having an internal screw-thread, *b*, to receive a screw-thread, *b* $\times$, cut on the exterior of the inner end of the other part, B, of the handle, as shown clearly in both figures.

The inner end of the part B of the handle has an inward-projecting flange, *e*, extending all around it to fit in a groove, *d*, made in the shank, *e*, of a cylindrical key, C, which works within the socket *a*. This key C has a longitudinal groove, *e'*, made in its exterior to receive a pin, *f*, which projects from the inner surface of the socket, the pin and groove preventing the key from turning in the socket, (see fig. 1.)

The outer end of the key C has a V-shaped groove, *g*, made in it, and a square hole, *h*, is made centrally in the upper and lower part of the socket *a*, as shown clearly in fig. 2.

The shank of the auger, shown in red, is clamped firmly in the handle by passing it through the openings or holes, *h* *h*, in the socket, *a*, and screwing up the parts A B, so that the key C will press against the shank within the socket, as will be fully understood by referring to fig. 2.

This auger-handle may be constructed at a small cost. It is extremely strong, and durable, and may be readily applied to and detached from the shank of the auger.

Having thus described my invention, I claim as new, and desire to secure by Letters Patent—

The cylindrical key C, within the handle A B, provided at its front end with the V-shaped groove *g*, and upon its under side with the longitudinal groove *e'*, fitting over the lug *f* in the socket *a*, and having at its rear end the circumferential groove *d*, fitting over the lugs *b* upon the part B of the handle, all constructed and operating as described, whereby, as the parts A B are screwed together, the key C is operated longitudinally to clamp the shank of the auger, as herein set forth and represented.

JAMES SWAN.
